UNITED STATES PATENT OFFICE.

GEORGE H. REYNOLDS, OF NEW YORK, N. Y., ASSIGNOR OF TWO-THIRDS TO CORNELIUS H. DELAMATER AND GEORGE H. ROBINSON, BOTH OF SAME PLACE.

AIR-COMPRESSING MACHINERY.

SPECIFICATION forming part of Letters Patent No. 272,771, dated February 20, 1883.

Application filed May 3, 1882. (No model.)

To all whom it may concern:

Be it known that I, GEORGE H. REYNOLDS, of the city and county of New York, in the State of New York, have invented certain new and useful Improvements in Air-Compressing Machinery, of which the following is a specification.

One part of my invention relates to air-compressors in which the cooling of the compressing-cylinder is effected by discharging cooling-water directly into the cylinder and against the piston.

The invention consists in the combination, with the cylinder and piston of an air-compressor, of a steam-engine for operating the same, having a cut-off-valve gear actuated by an eccentric, and a pump operated from said eccentric for delivering water into the ends of the cylinder and against the face of the piston, whereby the water is converted into spray and made very effective in cooling.

The invention also consists in the combination, with the compressor-cylinder and means for delivering cooling-water into said cylinder, of a chamber arranged between said cylinder and the storage-tank for compressed air, and means for conducting air and water together from said cylinder to said chamber and allowing of the escape of the water from said chamber independently of the air. The pipe or conduit which is employed as a means of conducting air and water from the compressing-cylinder to said chamber is preferably provided with a check-valve, independent of the discharge-valves of the compressor, for preventing the return of water and air.

The invention also consists in a novel method of securing a suction-valve for an air-compressor upon its valve-stem, whereby the valve is tightened upon its stem by its impact in closing.

The invention also consists in a novel form of stop for the suction-valve.

The invention also consists in a novel form of yielding stop for the discharge-valve of an air-compressor, for limiting the opening of said valve.

The invention also consists in the combination, with an air-compressing cylinder, of a

frame, to the side of which said cylinder is secured, and which is provided at the side of the cylinder with a tool-box having an opening on the side of the frame opposite to that on which said cylinder is secured. The heat of the compressing-cylinder will prevent oil in oil-cans placed in the tool-box from congealing in cold weather.

The invention also consists in details of construction and combination of parts hereinafter described and claimed.

In the accompanying drawings, Figure 1 represents a plan of a double-acting air-compressor embodying my invention and its operating-engine. Fig. 2 represents a transverse vertical section, upon the dotted line *x x*, Fig. 1, of the chamber into which the water and air are delivered from the compressor, together with its appurtenances, and upon a larger scale. Fig. 3 represents a longitudinal section of one of the suction-valves upon a larger scale. Fig. 4 represents a similar section of one of the discharge-valves upon the same scale as Fig. 3. Fig. 5 represents a partial longitudinal section of the air-compressing cylinder on a larger scale. Fig. 6 represents a transverse section thereof on the same scale as Fig. 5, and Fig. 7 represents a partly-sectional plan of the operating-engine shown in Fig. 1.

Similar letters of reference designate corresponding parts in the several figures.

A designates the motor or steam-cylinder, and B designates the compressor-cylinder, both of which are secured to a common bed-plate or frame, C. The pistons of both cylinders A and B are connected to a common piston-rod, A'; and D designates the connecting-rod, and E the crank through which the steam-piston transmits motion to the crank-shaft F. A similar engine operating a second air-compressor cylinder may be connected with the crank-shaft F, and in such case the two cranks should be set at right angles to each other, so that while one engine is on the center the other is exerting its maximum power. I provide the compressing-engine with a double-acting pump, G, which may be of any suitable construction, and as here shown is oper-

ated by an eccentric, G' , on the crank-shaft F . The engine here shown is provided with cut-off-valve gear, as shown in Fig. 7. G^2 designates the main slide-valve, and G^3 the cut-off valves, which are operated through a rod, G^4 . The rod from the eccentric G' is arranged between the pump G and the valve-rod G^4 , and is connected by a cross-head, G^5 , with the piston of the pump and the said valve-rod. It will therefore be seen that the same eccentric operates the cut-off-valve gear and the pump. The pump-piston and the piston in the compressor-cylinder B are always moving in the same direction, or simultaneously backward and forward, and I connect the two ends of the pump G by pipes $a a'$ with the corresponding ends of the compressor-cylinder B . Water is discharged through the pipes $a a'$ into the ends of the cylinder B , and, striking against the piston, is converted into spray, thus bringing it into such direct and intimate contact with the air that it is very effective in cooling. It will be observed that when the water is being discharged through either pipe a or a' the compressor-piston is moving toward the end of the cylinder at which the water enters. The water and the piston, always moving in opposite directions, are opposed to each other. The compressor-cylinder B is provided with one or more suction and discharge valves at each end, as seen in Fig. 1, and though these valves may be of any suitable construction, I prefer to use those shown in Figs. 3, 4, and 5.

Referring first to Fig. 3, H designates the socket or shell of the valve, which is screwed into the head B' of the cylinder, and has at its inner end a valve-seat, b . I designates the valve which is fitted to this seat, and I' designates the stem, which is adapted to slide in a suitable guide, b' . The valve is held to its seat, in the usual way, by a spring, c . Beyond the guide b' the stem I' is surrounded by a sleeve, c' , which is placed between washers c^2 , and the sleeve and washers are secured on the valve-stem by nuts c^3 . The spring c surrounds the sleeve between the two washers, and it is obvious that when the valve opens to the desired extent the washer c^2 adjacent to the nuts c^3 will strike against the end of the sleeve, and the latter therefore will form a stop to prevent the valve opening to an undesirable extent. The guide b' might be extended, so as to itself form the stop.

I make the valve I and stem I' of two separate pieces, and in the valve is a hole, d , which tapers from the back of the valve toward its face, or in the direction in which the valve moves to seat itself, and fits a corresponding tapered portion, d' , on the inner end of its stem I' . The stem I' is driven into the hole d from the back of the valve, and hence the constant working of the valve will only tend to force it tighter on the stem. To further secure it I may rivet the valve down over the end of the stem, as at d^2 .

Referring now to Figs. 4 and 5, which rep-

resent the discharge-valve, B^2 designates an air chest or space, which is formed in the head B' at the point where the discharge-valves are placed, and which communicates with a passage, B^3 , below the cylinder, as shown in Fig. 5. J designates the cylindric socket in which the hollow valve J' works. The head B' has formed in it a seat, e , on which the valve J' closes, and it is held to its seat by a spiral spring, e' . The socket J is closed at the outer end by a plug or bonnet, J^2 , and in the inner end thereof is formed a socket, f , in which a stronger spiral spring, f' , fits. When the valve J is closed the end of the spring f' does not bear against it, but is at a considerable distance therefrom. When the valve opens, however, it is forced against the spring f' , which constitutes a yielding stop for limiting the movement of the valve and preventing its hammering. A rubber stop has been before used in place of the spring f' , but is very unsatisfactory, because the heat of the air rapidly softens or melts the rubber and renders it worthless. The compressed air passes from the air chests or spaces B^2 in the heads of each cylinder B to the passage B^3 , and then escapes through a discharge pipe or conduit, K , (shown clearly in Figs. 1 and 2,) which is connected with the passage B^3 , as shown in Figs. 5 and 6. Adjacent to the cylinder B , and between it and the storage-tank for compressed air, (not here shown,) is located a chamber, L , represented as composed of a base portion and a cylinder mounted thereon, (see Fig. 2,) and the compressed air and water from the cylinder B pass together through the pipe or conduit K into the chamber L , whence they issue through a check-valve, K' . The height of the water in the chamber L is controlled by a discharge cock or valve, g , and float g' ; and M designates a water-gage, which may be applied to the chamber L .

Where two compressing-engines are employed, as before described, two pipes or conduits K are used, and one pipe or conduit is here shown as broken off. The air passes up through the water in the chamber L , by which it is both cooled and dried, and is then delivered from the top of the chamber through a pipe, N , whence it passes to the storage-tank.

In the use of air-compressors many small tools are required, and I form in the frame C , adjacent to the compressor-cylinder B , a tool-box, having an opening which is closed by doors C' , (shown clearly in Fig. 1,) on the side of the frame opposite to that on which is the cylinder B . Such a tool-box is very desirable, inasmuch as the heat of the compressor-cylinder is sufficient to prevent oil contained in oil-cans in the tool-boxes from becoming congealed by cold, even when the compressor is located in an exposed position.

What I claim as my invention, and desire to secure by Letters Patent, is—

1. The combination, with the cylinder and piston of an air-compressor, of a steam-engine

- for operating the same, having a cut-off-valve gear and an eccentric for actuating the same, and a pump operated from said eccentric for delivering water into the ends of the cylinder 5 and against the face of the piston, whereby the water is converted into spray, substantially as specified.
2. The combination, with the cylinder and piston of an air-compressor, of means for delivering water directly into the cylinder during the movement of said piston, a chamber arranged between the cylinder and the air-storage tank, and means for conducting the water and air together from said cylinder to 15 said chamber, and for allowing the escape of the water independently of the air, substantially as specified.
3. The combination, with the cylinder and piston of an air-compressor, of means for delivering water directly into the cylinder during the movements of said piston, a pipe or conduit for conducting the water and air together from said cylinder, and a check-valve in said pipe or conduit, independent of the discharge-valves of the compressor, for preventing the return of water and air, substantially as specified.
4. The combination, with the air-compressor cylinder B and its piston, of means for delivering water into the cylinder during the movement of the piston, the pipe or conduit K, through which the water and compressed air are to be conducted together, the chamber L, with which said pipe or conduit communicates, 35 and which is provided with the escape-pipe N for air, the check-valve K' in said pipe or conduit K, for preventing the return of air and water, and the cock g' and float g' for controlling the escape of water from said chamber, 40 substantially as specified.
5. The combination, with a suction-valve for an air-compressor, having in it a hole tapering in the direction in which said valve moves in
- closing, of a valve-stem having its inner end correspondingly tapered and driven into and 45 through said hole from the back of the valve, whereby the impact of the valve in closing tends to tighten it upon said stem, substantially as specified.
6. The combination of the valve-stem I', having the taper portion d', and the valve I, having the taper hole d, into which said stem is driven, said valve being riveted over the end of the stem at d², substantially as specified.
7. The combination, with a suction-valve and 55 its stem, of a guide or sleeve surrounding the valve-stem and forming a stop for limiting the opening movement of said valve, substantially as specified.
8. The combination, with the suction-valve I and its stem I', of the guide b', the loose sleeve c', and the spring e, substantially as specified.
9. The combination, with the suction-valve I and its stem I', of the guide b', the loose 65 sleeve c', the spring e, the washers c², and the nuts c³, substantially as specified.
10. The combination, with the discharge-valve J for an air-compressor, and its seat e, of the spring e' for holding said valve to its 70 seat, the socket f, and the metallic spiral spring f' in said socket, forming a yielding stop to limit the movement of the valve, substantially as specified.
11. The combination, with an air-compressing cylinder, of a frame to the side of which said cylinder is secured, and which is provided at the side of the cylinder with a tool-box having an opening on the side of the frame opposite to that on which the cylinder is secured, 80 substantially as and for the purpose specified.
